UNITED STATES PATENT OFFICE.

CHARLES L. NEWCOMB, OF HOLYOKE, MASSACHUSETTS, ASSIGNOR TO THE DEANE STEAM PUMP COMPANY, OF SAME PLACE.

PUMP-CYLINDER PACKING.

SPECIFICATION forming part of Letters Patent No. 593,027, dated November 2, 1897.

Application filed July 13, 1896. Serial No. 599,039. (No model.)

To all whom it may concern:

Be it known that I, CHARLES L. NEWCOMB, a citizen of the United States, residing at Holyoke, in the county of Hampden and State of Massachusetts, have invented a new and useful Improvement in a Packing for Pump-Cylinders, of which the following is a specification, accompanied by drawings forming a part of the same, in which—

10 Figure 1 represents a central vertical sectional view of a pump-cylinder embodying my invention. Fig. 2 is a front elevation of the same. Fig. 3 is a central vertical sectional view of the metallic bushing forming a portion of my improved packing. Fig. 4 is a top view of the same, and Fig. 5 is a side and detached view of the upper or removable gland.

Similar letters refer to similar parts in the different figures.

20 The object of my invention is to provide the pump-cylinder of a pumping-engine with a centrally-packed reciprocating plunger comprising a metallic bushing which is readily removable and capable of being replaced by the ordinary packed stuffing-boxes; and it consists in the construction and arrangement of the several parts, as hereinafter described, and set forth in the annexed claims.

Referring to the drawings, A denotes the 30 upper section, and A' the lower section, of a double-acting pump-cylinder, said sections being united together by flanges A² and bolts A³, leaving a space between the sections A and A'. The opposing ends of the two sections A A' are provided with concentric openings to receive a reciprocating plunger B, having a plunger-rod B', through which the reciprocating motion is imparted to the plunger by means of a steam-engine or other motive 40 power. Inclosing the central section of the plunger is a metallic bushing C, formed in two parts C' and C², provided with flanges C³ and C⁴, which are united by a series of bolts C⁵. The opening in the lower chamber A' to receive the plunger B is made to fit the plunger, except at its upper end, where it is enlarged to receive the lower end of the bushing and form an annular chamber C' around the bushing to receive a packing. The lower portion C² of the bushing is provided with a flange

C⁸, which is bolted to the lower section of the water-cylinder.

The opening through the upper section of the water-cylinder is larger than the plunger B, forming an annular chamber D to receive the upper end of the metallic bushing, and the opening is still further enlarged at its lower end to form an annular chamber D' around the bushing to receive a packing, and the annular chamber D' is closed by the gland E, 60 provided with a flange E', which is bolted to the upper section of the water-cylinder.

The upper end of the upper section A of the water-cylinder is provided with an opening large enough to allow the insertion or removal 65 of the plunger B, said opening being closed by a cap F.

When the metallic bushing C is in place, the annular chamber D' in the upper section of the cylinder is packed around the metallic 70 bushing and secured by the gland E, and the annular chamber C' in the lower section of the cylinder is packed and the packing is secured by bolting the flange C⁸ to the cylinder.

When it is desired to remove the metallic 75 bushing and packing, the cap F is removed and the plunger B raised above the joint in the metallic bushing at the flanges C³ C⁴, and the metallic bushing is readily removed through the space between the upper and 80 lower sections of the cylinder by disconnecting the upper and lower portions of the bushing by the removal of the bolts C⁵. The gland E is loosened and the packing in the annular chamber D' removed, and the upper portion 85 of the metallic bushing is then raised by sliding it upwardly in the annular chamber D around the plunger. The bolts are then removed from the flange C⁸ and the lower portion C² of the bushing removed, after which 90 the upper portion C', together with the gland E, are removed downwardly. If the use of a metallic bushing is not desirable, a short bushing is inserted at the lower end of the annular chamber D, in order to close the space 95 around the plunger, and the annular chamber D' will then form a stuffing-box which can be packed and closed by a gland in the ordinary manner. The annular chamber C' may also be packed and closed by an ordinary 100

gland, thereby packing the plunger at the lower end of the upper section A and at the upper end of the lower section A'.

What I claim as my invention, and desire

5 to secure by Letters Patent, is—

1. The combination with a pump-cylinder comprising sections with an intervening space between said sections, and a reciprocating plunger, of a metallic bushing inclosing the central section of said plunger with its ends entering said cylinder-sections, said bushing being made in separable parts united at their ends, one of said parts being capable of sliding into one of said cylinder-sections, substantially as described.

2. The combination with a pump-cylinder comprising sections with an intervening space between said sections and a reciprocating plunger, of a metallic bushing made in parts, one of said parts having a flange by which it is united to one of said cylinder-sections, and a movable gland carried on the other part of said bushing and adapted to enter a stuffing-box in the other cylinder-section, substantially as described.

Dated this 9th day of July, 1896.

CHARLES L. NEWCOMB. [L. S.]
